UNITED STATES PATENT OFFICE.

HENRY H. WHEELER, OF EAST ST. LOUIS, ILLINOIS.

VALVE.

SPECIFICATION forming part of Letters Patent No. 635,214, dated October 17, 1899.

Application filed April 12, 1899. Serial No. 712,757. (No model.)

To all whom it may concern:

Be it known that I, HENRY H. WHEELER, a citizen of the United States, residing at East St. Louis, in the county of St. Clair and State 5 of Illinois, have invented certain new and useful Improvements in Valves; and I do hereby declare the following to be a full, clear, and exact description of the invention, such as will enable others skilled in the art to which 10 it appertains to make and use the same.

My invention relates to improvements in valves; and it consists in the novel combination and arrangement of parts, as will be hereinafter more particularly described, and 15 pointed out in the claim.

In the drawings, Figure 1 is a combined section and side elevation of my complete invention, and Fig. 2 is a vertical transverse section taken on the line $x-x$ of Fig. 1.

20 The object of my invention is to construct a valve to be used more particularly in connection with water-mains wherein a hose or other pipe is to be attached for directing the water to any given place, and is designed to 25 keep up the circulation of water below the piston of the same when the latter is in a closed position, thereby preventing the water from freezing, the small amount of water escaping being conducted to any suitable reservoir or other place. When the piston or valve 30 is in an open position for supplying water, the pressure of the latter is greatly relieved or reduced, and consequently very little of the same is lost.

35 Briefly stated, the invention consists of a valve-casing of any suitable design, having an inlet and outlet for the passage of the water, a piston which is adapted to be moved to and from a suitable valve-seat for regulating the 40 supply of water through the valve, an annular chamber formed in the casing at a suitable distance from the valve-seat, ports formed in the inner wall of the casing and in communication with said annular chamber, screw-threaded openings formed in the outer wall 45 surrounding the chamber, and screw-threaded plugs adapted to be screwed into said screw-threaded openings for closing any number of the screw-threaded openings, all of which will 50 appear in the detail description now to follow.

Referring to the drawings, 1 represents a valve-casing of any suitable design and pro-

vided with a screw-threaded extension 2, by means of which the said casing may be secured to the water-main in the well-known 55 manner. As shown in the drawings, a screw-threaded cap 3 covers the opposite open end of the valve-casing 1 and is provided with an extension 4 and the usual stuffing-box, (not shown,) through which a screw-threaded piston-rod 5 passes, the inner end of which loosely carries a piston 6 or other valve, which 60 co-operates with the annular seat 7, all of which is constructed in the well-known manner, the said casing being provided with an 65 outlet 8, which is arranged at an incline, through which the water passes when the piston or valve is in an open position or moved out of contact with the annular seat 7, said outlet being provided with the usual exterior 70 screw-threads 9, by means of which a hose or other pipe is attached for supplying water to any desired place.

Formed in the valve-casing, adjacent to the threads 2 of the same, is an annular chamber 75 10, which is formed by the inner smooth circular wall 11 and the outer wall 12, the said annular chamber being in communication with the interior of the valve by small circumferentially-arranged ports 13, formed in 80 said wall 11, through which the water is adapted to pass and into the said annular chamber. Formed in the outer wall 12 of the valve-casing are any number of screw-threaded 85 openings 14, which are adapted to receive screw-threaded plugs 15, one of said plugs being usually removed, leaving the screw-threaded opening for the purpose of attaching a pipe, which leads to any suitable reservoir or other place, whereby when the piston 90 or valve 6 is in a closed position a small amount of water is permitted to pass through the ports 13 into the annular chamber 10 and out through one of the larger screw-threaded 95 openings 14, to which a pipe is attached, and thus a small amount of water is permitted to circulate and prevent the water from freezing within the valve-casing and water-main, to which the same is attached.

The object of having a number of screw-threaded openings 14 and plugs to close all but one of said openings is for the purpose of being able to place the valve in any position, should occasion require it, whereby the proper

plug may be removed to more effectually drain the annular passage or chamber 10.

I do not limit myself to the application of my invention to the particular construction 5 of valve herein shown and described, as it is evident that the same may be applicable to any design or construction of valve without departing from the nature of my invention.

Having fully described my invention, what 10 I claim is—

A valve comprising a suitable casing, an annular valve-seat formed in the same, a valve or piston coöperating with said seat, an annular chamber surrounding the casing, and 15 located adjacent to the valve-seat, said chamber forming inner and outer walls, the said inner smooth wall being provided with small circumferentially - arranged ports, whereby

the annular chamber is in communication with the interior of the valve-casing, the outer wall being provided with large screw-threaded openings, and screw-threaded plugs adapted to be screwed into each of said screw-threaded openings, one of which plugs may be removed for the passage of water located within the 20 annular chamber, whereby the valve may be placed in any suitable position for the proper drainage of water contained in the annular chamber, substantially as described.

In testimony whereof I affix my signature 25 in presence of two witnesses.

HENRY H. WHEELER.
